United States Patent Office

Des. 184,312
Patented Jan. 27, 1959

184,312

PORTFOLIO LOCK

Charles S. Gehrie, Montclair, N. J., assignor to Presto
Lock Co., Garfield, N. J., a limited partnership

Application January 10, 1958, Serial No. 49,185

Term of patent 14 years

(Cl. D50—7)

Fig. 1 is a front elevational view of a portfolio lock, showing my new design and

Fig. 2 is a top plan view of the same.

I claim:

The ornamental design for a portfolio lock, as shown.

References Cited in the file of this patent

UNITED STATES PATENTS

D. 148,063   Grosz   Dec. 9, 1947
T. M. 37,580   The Protectine Co.   Dec. 31, 1901